UNITED STATES PATENT OFFICE.

JESSE K. RUSSELL, OF MARION, ILLINOIS.

WAGON-COVER.

1,028,608.

Specification of Letters Patent.

Patented June 4, 1912.

Application filed April 17, 1911. Serial No. 621,603.

To all whom it may concern:

Be it known that I, JESSE K. RUSSELL, a citizen of the United States, residing at Marion, in the county of Williamson, State of Illinois, have invented certain new and useful Improvements in Wagon-Covers; and I do hereby declare the following to be a full, clear, and exact description of the invention, such as will enable others skilled in the art 10 to which it appertains to make and use the same.

This invention relates to covers for wagon bodies and the object of the invention is to provide an absolutely rain proof cover, 15 whereby the supplies or other articles carried within the wagon will be efficiently protected from inclement weather.

A further object of the invention is to construct a cover of sheet metal and to so 20 attach the same to the body of the vehicle or to the sides of the wagon bodies that it may be readily detached when not needed for use.

A still further object is to provide a cover having a novel frame structure, side doors 25 and rear doors, said parts being so connected and fitted together, that the entrance of rain or snow into the wagon is prevented.

The invention consists of certain other combinations and arrangements of parts, as 30 will be hereinafter more fully described and clearly specified in the appended claims.

In the drawings:—Figure 1 is a side elevation of a conventional form of wagon body with my improved cover attached thereto. 35 Fig. 2 is a central longitudinal sectional view on the line 2—2 of Fig. 3. Fig. 3 is a sectional view on the line 3—3 of Fig. 1. Fig. 4 is a rear end view of the cover attached to the body. Fig. 5 is a sectional view taken 40 on the line 5—5 of Fig. 1. Fig. 6 is a detail sectional view of the rear end of the body and its hinged door, showing the same in an open position. Fig. 7 is a detail view of one of the sliding side doors and its guide 45 members.

Referring to the drawings in detail, there is shown a wagon body or box 10 having side portions, forward and rear ends secured to a suitable flooring 11, and carried by suitable supporting wheels 12 which may be of any preferred form or design. Arranged adjacent the front end of the body or spaced therefrom, to allow sufficient room for the driver's feet is a seat structure 13 rearwardly of which my improved cover is dis-

posed and secured detachably to the sides of the wagon body.

As is shown in the drawings, the top and sides of the cover are formed of a single section of sheet material, such as metal, the top 14 being sufficiently rounded to provide a drain surface so that any water discharged on to the side portions 15 will be prevented from entering the wagon body due to the fact that the lower edges of the sides which are bent upwardly to form a suitable binding as shown at 16 are extended outwardly of the sides of the body. The forward and rear ends of the top or cover forming section are also bent inwardly in a similar 60 manner as shown at 16 and the forward end 17 has its edges turned at right angles and secured to an arched brace 18 in conjunction with the top and side portions of the cover by means of rivets or the like 19. The 65 braces have their lower ends extended inwardly and downwardly as shown at 20 to engage the inner faces of the side portions of the body and are detachably secured by means of bolts 21, and crank nuts 22. The 70 forward end is also braced by a yoke member 23 which is preferably constructed of strip iron and which has its lower ends extended between the forward end 17 and its 75 upturned bottom portion or edge which latter abuts a transverse strip 24 preferably 80 constructed of wood and secured to the bottom 11 by means of screws or the like 25. Between this strip and the bottom is placed a felt or leather packing 26 which excludes 85 the entrance of rain or moisture from beneath the front end of the cover. The arched braces 18 are provided at the forward and rear end of the cover in a similar 90 manner and at other intervals as desired and as may be found necessary in accordance 95 with the length of the same. The forward and lower portion of the sides 15 or the section of metal forming the same is cut away 100 to form a rectangular opening as shown at 105 27 so that the side edges of the front end 17 which are secured to the forward arched braces 18 may be securely attached upon its inner face as shown and the adjacent edges 110 of the cut away portions are turned inwardly in a similar manner as the lower end portions of the material forming the top and sides of the cover. Sliding side doors 28 are arranged to cover the openings 27 and are provided with handles 29 for their ma-

nipulation, said sliding doors being mounted upon longitudinal guides 30 which are secured at their forward ends to the arched braces 18 and at their rear ends to the sides 5 of the cover. The upper edges of the sliding doors or sections of metal forming the same are coiled around the guide rods 30 as shown at 31 so as to permit their free sliding movement within the longitudinal 10 keeper guides 32 which are formed of heavy sheet metal secured to the sides and which have their lower ends turned upwardly to receive the bottom edges of the doors. Each of the doors is also provided with a cut away 15 portion 33 adjacent the forward and upper edges so as to permit the doors to move the full extent of the sides which have their in-turned forward extremities projecting beyond the forward end of the cover, said in-turned 20 portions serving to form a weather proof joint. In order to limit the movement of the sliding doors, each of the said covers is provided with a U-brace 34 upon its inner side, the upper end portions of which 25 are coiled over the convolute portions 31 which are slidable upon the guide rods 30 so as to engage the lower ends of a semi-arched brace 35 which are also fitted to slidably receive the upper edges of the doors. 30 By this construction it will be apparent that as the doors are closed, the rearmost arms of the members 34 will engage the extremities of the semi-arched braces 35 thus preventing further movement of the doors 35 whereas in the opening of the doors, the forward ends of the members 34 will engage the forward edges of the semi-arched brace at their lower ends thus limiting their movement in that direction and preventing contact 40 of the handles 29 with the rear edges of the cut-away portions or openings over which the doors are movable. By reason of these guide members and the fact that the doors are located upon a vertical line outside 45 of the outer faces of the sides of the body, drippings from the top and sides of the cover will not escape into the body to destroy the articles which may be carried therein. The securing bolts 21 for the lower 50 ends of the arched braces are also adapted to carry the guide brackets 36 which are offset at their upper ends to receive the lower and forward edges of the sliding doors and which at their lower ends are formed with 55 sharpened projections or burs 37 adapted to be driven into the sides of the body, thereby securely holding the same against pivotal movement upon the bolts and serving to prevent outward movement of the forward 60 ends of the doors. Similar guides or brackets may also be secured to the sides of the body adjacent the rear edges of the openings 27 so as to hold the side portions of the cover closely adjacent to the doors and preventing 65 the entrance of moisture. The rear

end 38 of the cover is also secured to the section of metal forming the top and sides in a similar manner as the forward end 17 and said end is provided with a central opening having inturned edges and adapted to be closed by a door 39 which is hingedly secured at its upper edge to the rear end of the cover as shown at 40 and adapted for outward movement thereon. The upper edge of the door 39 is offset inwardly and is adapted to engage the adjacent inner face of the rear end of the cover so as to form a lap joint which with the overlapping side edges of the door form a further moisture proof cover. 70 A vertical guide casing 41 is secured to the inner side of the rear end of the cover and has a weight 42 movable therein and to which is attached a flexible connection 43 which extends over a pulley 44 mounted vertically thereabove and within the rear end forming section, said connection extending and being attached to the adjacent side of the door near its lower edge so as to normally hold the door in an elevated position. 75 A transverse pin 45 is extended through the casing and adapted to limit the downward movement of the weight and the consequential vertical swing of the door. Pivotal latches 46 are also provided upon the rear 80 end wall of the cover to retain the door in a closed position and in order to strengthen the said portion of the cover, vertical reinforcing strips 47 are provided upon its inner side which may be further reinforced 85 and secured to the sides of the cover by the angular braces 48. 90 From the foregoing description it will be readily apparent as the cover is secured to the side portions of the body by means of 95 bolts 21 and the lever nuts 22, said cover may be readily detached when desired and it will be further apparent with the sliding doors that the forward sides of the cover and the hinged door, connected in the manner set forth as well as the formation of the forward and rear ends of the cover, the entrance of rain or snow within the body and cover is prevented. The cover also 100 comprises a novel arrangement of braces 105 which will render the same very durable in use. 110

I claim:—

1. The combination with a wagon body having side and end portions, of a cover for the body, said cover comprising a top and sides formed of a single section of material, said top portion being rounded, arched braces secured to the section of metal forming the top and sides, said braces having 120 their lower ends offset inwardly, means detachably securing said offset portions to the sides of the body, forward and rear end portions for the cover and a closure mounted 125 in the rear end. 130

2. A cover for vehicles comprising a top, braces secured to the top, sides formed by downturned portions of the top, means for detachably securing the lower ends of the 5 braces to a wagon body, the surrounding edges of the top and sides being bent upon themselves, forward and rear ends for the cover, said ends being positioned inwardly of the forward and rear edges of the top 10 and sides and having inturned portions secured to the braces and movable closures for the sides and rear end of the cover.

3. In a cover of the class described, the combination with a vehicle body, of a cover 15 formed of a section of metal having downturned side portions, the top of the cover being rounded, said sides being located outwardly of the sides of the vehicle body, a forward end for the cover, said forward end 20 extending into contact with the bottom of the body, and a transverse strip in contact with said forward end to form a moisture proof joint.

4. In a cover having a top, sides, forward and rear ends, the combination with 25 suitable braces therefor, of guideways secured at their forward ends to the braces, said sides having openings therethrough, covers having their upper ends engaged

upon the guideways, a U-brace adapted for 30 limiting the movement of the covers in either direction and handles therefor.

5. In combination with a vehicle body, of a cover for the body, said cover having its top and sides formed of a single section of 35 sheet metal, forward and rear ends for the cover having inturned edges, braces for securing said inturned portions of the ends to the top and side portions, guide rods secured longitudinally within the cover adjacent the forward portion thereof, 40 slideable doors mounted upon the guide rods and movable over openings in the sides of the cover, guideways secured to said sections for receiving the lower edges of the 45 doors when opened, a semi-arched brace having end portions in which said doors are slideable and U-braces secured to the inner sides of the doors, said U-braces being adapted to contact with the ends of the 50 semi-arched brace to limit the movement of the doors in a closed or open position.

In testimony whereof, I affix my signature, in presence of two witnesses.

JESSE K. RUSSELL.
